STEAM VAPORIZER OR THE LIKE

Lawrence Katzman and Monte L. Levin, New York, N.Y.,
assignors to Kaz Manufacturing Co., Inc., New York,
N.Y., a corporation of New York

Filed June 12, 1963, Ser. No. 75,319

Term of patent 14 years

(Cl. D83—1)

FIG. 1

FIG. 2

FIG. 3

FIG. 4

FIG. 6

FIG. 5

FIG. 1 is a front perspective view of a steam vaporizer or the like embodying our new design and illustrating the appearance of one side thereof;

FIG. 2 is a top plan view thereof;

FIG. 3 is a side elevational view illustrating the opposite side from the side shown in FIG. 1;

FIG. 4 is a rear elevational view thereof;

FIG. 5 is a bottom plan view thereof; and

FIG. 6 is a partial cross sectional view taken on line 6-6 of FIG. 1.

We claim:

The ornamental design for a steam vaporizer or the like, as shown.
